Inventor
NOAH O. OARD.

John D. O'Farrell
Attorney

Patented Oct. 20, 1925.

UNITED STATES PATENT OFFICE.

NOAH O. OARD, OF COLUMBUS GROVE, OHIO.

POOL-BALL RACKER.

Application filed March 29, 1923. Serial No. 628,428.

To all whom it may concern:

Be it known that I, NOAH O. OARD, a citizen of the United States, residing at Columbus Grove, in the county of Putnam and State of Ohio, have invented certain new and useful Improvements in Pool-Ball Rackers, of which the following is a specification.

This invention relates to new and useful improvements in pool ball rackers and has for its principal object to provide means for quickly or expeditiously delivering or transferring the pool balls from the rack to the pool ball frame preparatory to "racking" or placing the balls in position for play at the commencement of the game.

With the foregoing and other objects in view that will appear as the nature of my invention is better understood the same consists in the novel features of construction, combination and arrangement of parts illustrated in the drawings and more particularly pointed out in the appended claim.

In the accompanying drawings, which are for illustrative purposes only and are therefore not drawn to scale:—

Figure 1 is a perspective view, illustrating the application of my invention.

Figure 2 is a front elevation of my pool ball racker, with the ball trough or chute in upright or inoperative position and part of the frame broken away to more clearly illustrate the invention.

Figure 3 is a vertical longitudinal transverse section, taken on the plane indicated by the dotted lines 3—3 of Figure 2.

Figure 4 is a vertical longitudinal section taken on line 4—4 of Figure 2 and Figure 5 a horizontal section, taken on line 5—5 of Figure 2.

Referring to the drawings for a more particular description of my invention and in which drawings like parts are designated by like reference characters throughout the several views, A designates the pool ball rack, B the triangular pool ball frame and C the table. The rack A is provided at the top, adjacent its upper corners, with the vertical ears or lugs 1 and at the bottom, adjacent the lower left hand corner, with the depending ear or lug 2 for convenience in fasten-

ing to the wall or other support; also with the usual series of vertically spaced shelves 3 for supporting the pool balls 4.

In carrying out my invention, the frame A is provided below the lowermost shelf 3, with a rectangular oblong compartment 5, of a length somewhat greater than the width of the rack. This compartment is provided with the upper downwardly and inwardly inclined ball race 6 provided at its inner end with a transverse opening 7 of a size corresponding to or slightly greater than the diameter of the pool balls and with a second lower downwardly but oppositely inclined ball race communicating with the transverse delivery opening 9 in the front wall 10 of compartment 5.

A supporting leg 11 depends from the bottom and lower right hand corner of the compartment 5 of the rack and has secured to its opposite flat sides 11' the metal ball guards 12 which project somewhat above the bottom of the delivery opening 9.

One leaf or section, as 13, of a hinge 14, is secured by means of screws 15 or other equivalent means to the flat projecting upper edge portion 16 of the leg 11 while the other section, as 17, thereof, is fastened to the lower or inner recessed end 18, of the delivery trough or chute 19.

A hinge 20 has one leaf or section, as 21, rigidly fastened to the lower end of the delivery trough aforesaid and its opposite leaf or section 22 free to ride over the convex ar-

uate face 23 of the forwardly projecting shoulder 24 formed intermediate the ends of the supporting leg 11. A coil spring 25 is disposed around the cross pin 26 of the hinge 20 the tendency of which is to hold or maintain the trough or chute 19 in

raised position, as illustrated in Figures 1 to 3, inclusive. The free end of the trough or chute is provided with a cup-shaped mouth piece 28, of felt or other suitable material, which constitutes a stop for the pool balls in transferring the same from the rack to the triangular frame B.

The lower end of the supporting leg 11 is provided with a transverse opening 28 for the reception of a screw (not shown) or other fastening element.

In practice, assuming that the game is over and the pool balls are in the rack all ready to be transferred or delivered to the usual triangular frame B on the pool table C, the pool balls are pushed over the outer ends of the shelves 3 and drop into compartment 5. During this operation, the vertical guard posts 29 will prevent the balls from falling out of the rack. When the 10 balls have been delivered to the compartment 5, the trough or chute 19 is swung down with its free end resting on the table and the mouth piece or pocket 28 positioned directly over the triangular frame 3 when 15 the balls will pass out of the delivery opening 9 and roll down the trough or chute until striking the mouth piece 28 and discharging into the frame. After this operation, the trough or chute is again raised 20 and the balls placed in position for a new game.

My device is simple and economical in construction and highly efficient in operation. With its use, the pool balls may be 25 racked and placed in position for play in approximately 15 seconds time and with the minimum exertion on the part of the operator.

From the foregoing description taken in 30 connection with the drawings, it is thought that the construction, operation and advantages of my invention will be readily

understood without requiring a more extended explanation.

Having described my invention, what I 35 claim as new and desire to secure by Letters Patent is:—

In a device of the character specified, the combination with a rack having a lower compartment provided with upper and 40 lower downwardly and oppositely inclined ball races and a delivery opening, of a supporting leg depending from the bottom of the lower compartment and provided with a forwardly projecting shoulder having a 45 convex face, a delivery trough or chute hinged to the upper edge of the supporting leg in position to swing in a vertical plane and adapted to receive the pool balls discharged through the delivery opening 50 of the rack when in lowered position, a mouth piece at the free end of the trough or chute, a hinge having one leaf rigidly secured to the lower end of the delivery 55 trough or chute and its other leaf free to ride over the convex face of the forwardly projecting shoulder of the supporting leg and a coil spring disposed around the cross pin of the hinge and tending to hold the trough or chute in raised position. 60

In testimony whereof I affix my signature.

NOAH O. OARD.
